ATTORNEY

UNITED STATES PATENT OFFICE.

JAMES W. COOMBS, OF SEATTLE, WASHINGTON, ASSIGNOR OF ONE-HALF TO THOMAS H. MAJOR, OF SEATTLE, WASHINGTON.

GATE-HINGE.

1,374,437.

Specification of Letters Patent. Patented Apr. 12, 1921.

Application filed September 27, 1920. Serial No. 412,929.

To all whom it may concern:

Be it known that I, JAMES W. COOMBS, a citizen of the United States, residing at Seattle, in the county of King and State of Washington, have invented a new and useful Gate-Hinge, of which the following is a specification.

My invention relates to improvements in gate hinges, or the like, in which ball bearings are utilized to effect the results obtained; and the objects of my improvement are to provide a hinge for a gate that in operation will cause the gate to be slow-moving, self-closing and practically noiseless.

I attain these objects by the mechanism illustrated in the accompanying drawing, in which—

Figure 1 is a vertical sectional view of the hinge and the bracket on which it is mounted; Fig. 2 is an elevation of a portion of the hinge, showing an exterior spiral groove and a portion of an interior spiral groove located in reversed relation, said grooves affording channels for ball bearings; Fig. 3 is a front elevation of said bracket and a spindle having a spiral groove, about which other portions of the hinge are adapted to rotate; Fig. 4 illustrates a gate post and gate mounted thereon, with said hinge in operative position.

Referring to the drawings, the device comprises the casing 1, its interior being circular in cross-section. 2 represents an integral lug, interiorly threaded, by which the gate is attached to the hinge, and 3 a cap for the casing. 4 is a hollow cylindrical member which fits into and practically conforms to the interior of the body of the casing. It is provided on its exterior surface with a spiral groove 5, which is complementary to a spiral groove 6 located in the interior surface of the casing. Said member is also provided with an interior spiral groove 7, which is placed in reversed relation to the groove on the outside of said member. 8 is a spindle fixedly attached to a flat, circular base 11, said base also serving as the bottom of the casing. This spindle is provided with a spiral groove 9, which is complementary to the interior spiral groove of member 4. When the hinge is assembled, it presents a structure wherein the spindle 9 and the portion 11 comprise the central portion of the device and its base, concentric with the spindle the member 4 resting on the

base, said parts being covered by the casing and concentric therewith; the casing also resting on the base. The grooves heretofore mentioned, when the parts are thus assembled, present ball races circular in cross-section, as shown at 10; said races to be filled with ball bearings. As it will be noted in Fig. 1, the cap 3 is hollow, giving space between the spindle and the cap to allow the casing and its bearings to be raised or lowered, as will occur when the hinge is in operation, the spindle being independent of the cap. The cap, however, rests upon the casing and the member 4, so as to prevent the top edge of said member from rising above the top edge of the casing while the hinge is in motion. 12 illustrates a bracket to which the hinge is attached. In Fig. 4 is shown the method of attaching the hinge to an iron gate, through the means of the threaded lug 2 on the hinge and a threaded pipe on the gate. 13 designates means for attaching the upper portion of the gate to the post, the pin permitting an up and down play to correspond with a like motion of the hinge during its operation.

It will be noted that in Fig. 1 the casing is shown as raised from the base. This illustrates the position of the hinge when the gate is opened. Upon the release of the gate, its weight, coöperating with this ball-bearing hinge, causes the gate to be closed, slowly and noiselessly, the ball bearings creating less friction and wear to the parts than usually occur in gate hinges. In this device, there are no springs to lose their elasticity, the wearing parts are protected from the weather, and its construction insures durability.

The preferred form of the races for the ball bearings is that of spiral grooves as described, but changes in and modifications of said construction may be made without departing from the spirit of my invention or sacrificing its advantages.

I claim:

1. A device of the class described, comprising a spindle, a member concentric therewith and a casing concentric with said spindle and member, a plurality of ball bearings operatively disposed between said spindle and member and between said member and casing, whereby said hinge has free lateral movement to the right or left and will, when operatively placed, return to its

normal, closed position, means for supporting said hinge and for attaching a gate thereto.

2. A hinge, comprising a casing having a removable top, said casing provided interiorly with a spiral groove, mounted within the casing, a cylindrical member provided exteriorly with a spiral groove complementary to said groove in the casing and a spiral groove interiorly, said last named groove being located in reversed relation to the

exterior groove of said member, a second cylindrical member rotatably mounted within the first member, provided with a spiral groove complementary to said interior 15 groove of the first member, a plurality of ball bearings operatively located in said grooves, and means whereby lateral and up and down movements may be imparted to said hinge.

JAMES W. COOMBS.
